ATTORNEY

UNITED STATES PATENT OFFICE.

DWIGHT R. ATKINSON, OF ALBANY, ASSIGNOR OF ONE-HALF TO J. EDWARD DODGE, OF WATERFORD, NEW YORK.

RAIL-JOINT.

SPECIFICATION forming part of Letters Patent No. 404,764, dated June 4, 1889.

August 4, 1888. Serial No. 281,970. (No model.)

To all whom it may concern:

Be it known that I, DWIGHT R. ATKINSON, a citizen of the United States, residing at Albany, in the county of Albany and State of New York, have invented a new and useful 5 Rail-Joint, of which the following is a specification.

My invention relates to improvements in devices for fastening railway-rails together; 10 and the object of my invention is to provide a rail-joint by means of which two rails may be brought together end to end and held securely and positively in position without the use of bolts, screws, and spikes. I attain 15 this object by the mechanism illustrated in the accompanying drawings, in which—

Figure 1 is a section along the line *a b* on Fig. 2. Fig. 2 is a side elevation. Fig. 3 is a section along the line *c d* on Fig. 2 and on 20 Fig. 4. Fig. 4 is a plan. Fig. 5 is a detailed view of the wedge-shaped bar *F*, and Fig. 6 is a section along the line *n o*, showing the wedge locking device.

Similar letters refer to similar parts throughout the several views.

The railway-chair *P*, constructed of cast-iron, cast-steel, or other suitable material, is provided with lateral inwardly-projecting flanges *p p*. To each side of the upper surface of the chair *P*, about midway between its ends, I place the boss *K*, the lower part of which boss is square or oblong in form and of a thickness extending above the surface of the chair *P* equal to the thickness of the foot 30 of the rail at its outer edge, and the upper portion of the boss *K*, being triangular or *V*-shaped pointing inwardly and downwardly, extending from the top of the flange *p* to the square or oblong portion of the boss.

40 The feet of the rails *R* and *R'* have recesses cut into each side of their adjoining ends for the purpose of allowing the square portion of the boss *K* to fit therein, as shown in Fig. 4. It is apparent that the rails *R* and *R'* may 45 be arranged to come as near together as may be deemed advisable by constructing the recesses accordingly.

The object in fitting the rails with recesses into which the square portion of the boss *K* 50 is placed is to prevent the rails from "creep-

ing," which, under certain circumstances, they have a tendency to do. When two rails are thus placed onto the chair *P*, their feet fitted to the boss *K*, I place on each side of the rails resting upon the foot of each adjoining rail 55 the triangular wedge-shaped bar *F*, larger at one end than at the other, provided with the *V*-shaped notch *k*, into which the triangular portion of the boss *K* fits, preventing the longitudinal movement of the bar *F*. As thus 60 arranged the bar *F* has one of its sides resting upon the foot of each rail and one of its sides resting against the flange *p*, its remaining side forming an obtuse angle with the foot of the rail. Into the last-mentioned side 65 of the bar *F* is cut a groove extending from the larger end of the bar toward the smaller end a short distance and provided at the end of the groove with a notch or cavity, into which the hook *H*, formed at the end of the 70 steel key-bar *S*, is placed. The steel key-bar *S* has formed on its upper surface a latch-catch *v*, which engages with the notches *T T* on the surface of the wedge *W*. The groove into which the steel key-bar *S* is placed varies 75 in depth, being deeper near the end of the bar in order to allow the steel key-bar *S* to be depressed and thus removed from contact with the notches *T T* of the wedge *W* when it is desired to unlock it.

The wedge *W* is triangular in form and larger at one end than at the other, and is made to fit closely against the under side of the head and against the web of the rails *R* and *R'*, and also against the side of the bar *F*. 85 That side of the wedge *W* coming into contact with the bar *F* is provided near its smaller end with a series of *V*-shaped notches *T T*, which engage with the latch-catch *v* on the key-bar *S*, as shown in Fig. 6.

In order to place the wedge *W* into position, it is necessary to place its smaller end under the head of the rail and between the web and the side of the bar *F* nearest the smaller end of the bar *F* and drive it snugly home. The 95 smaller portion of the wedge *W* is in contact with the larger portion of the bar *F*, which approaches quite near the head of the rails and presses as tightly against and is as closely in contact with the web and under side of the 100

- head of the adjoining rails as it can be driven. The key S prevents it from withdrawing from contact with the bar F should there be sufficient vibration of the rail to make such a thing possible without it, and the boss K holds the bar F from moving backward or forward on the chair P. The wedge W is throughout its whole length in contact with the web of the rails, and also throughout its whole length
- 5 10 15
- in contact with the bar F, and as each side of the rails is provided with the same support, it follows, as a consequence, that the rails, wedges, bars, and chair form one solid mass, which cannot be separated by any accidental means.

I do not confine my invention to the wedge W partly in contact with the web and partly in contact with the head of the rail, as shown, but desire to call attention to the fact that these wedges would cause the device to be operative whether in contact with the head and foot of the rail, or with the head and web, or with the web, or with the head, foot, and web.

My rail-joint is very simple in its construction, convenient and easily placed in position, and positive and satisfactory in its operation.

What I claim as my invention, and desire to secure by Letters Patent, is—

1. In a railway-joint, a chair provided with lateral inwardly-projecting flanges and bosses placed on each side of the upper surface of the chair, provided with a lower portion square in form and an upper portion V-shaped, substantially as described, and for the purpose set forth.
2. In a railway-joint, the combination of a triangular wedge-shaped bar provided with a groove and notch, into which is placed a key-bar provided with a latch-catch, with a wedge 40 provided with a series of notches, with which the latch-catch engages, all substantially as described, and for the purpose set forth.
3. In a railway-joint, the combination, with a chair provided with lateral inwardly-projecting flanges, of triangular wedge-shaped bars placed in contact with the foot of the rails on both sides, and also in contact with the chair-flanges, and wedges in contact with the under sides of the rail-heads, and also in contact 45 50 with said bars, substantially as described.

4. In a railway-joint, the combination, with a chair provided with lateral inwardly-projecting flanges, of triangular wedge-shaped bars placed in contact with the foot of the rails on both sides, and also in contact with the chair-flanges, and wedges located in contact with the rail-webs and under sides of the rail-heads, and also in contact with said bars, substantially as described.

5. In a railway-joint, the combination of a chair provided with an inwardly-projecting flange and a boss projecting inward from said flange, said boss having a lower squared portion to fit recesses in the adjacent ends of the rails and provided with an upper inwardly-projecting V-shaped portion, a triangular wedge-shaped bar having a notch to fit the V-shaped portion of said boss, said bar being placed upon the foot of each rail and in contact with the chair-flange, and a wedge driven 70 in contact with the under side of the head of each rail, and also in contact with said bar, substantially as described.

6. In a railway-joint, the combination of a chair provided with lateral inwardly-projecting flanges and bosses projecting inwardly from said flanges, said bosses each having a lower squared portion and an upper inwardly-projecting V-shaped portion, the rails having recessed ends to fit the squared portions of said bosses, triangular wedge-shaped bars notched to fit said bosses and placed upon the foot of each rail on both sides and in contact with the chair-flanges, and wedges driven in contact with said rails and bars on both sides, 85 substantially as described.

7. In a railway-joint, the combination of a chair provided on both sides with inwardly-projecting flanges, triangular wedge-shaped bars resting on the rail-feet in contact with the chair-flanges and provided on their inner sides with key-latches, and wedges driven in contact with said rails and bars on both sides of the rails, and provided with notches to engage the key-latches, substantially as de- 90 95 scribed.

DWIGHT R. ATKINSON.
